WORK HANDLING DEVICE

Malcolm H. Freeman, Maryville, Tenn., assignor
to Aluminum Company of America, Pittsburgh,
Pa., a corporation of Pennsylvania

Application October 4, 1939, Serial No. 297,906

10 Claims. (Cl. 294—88)

This invention relates to improved work handling devices. More particularly it relates to work handling tongs adapted to grasp and carry articles such as coils, slabs, ingots, building materials, packages, and the like, especially in a form adapted for use with a crane, hoist, or other type of lift.

An object of this invention is to provide an improved work handling device adapted to be associated with a lift and adapted to clamp, raise, convey, and deposit articles of varying size and shape, particularly articles which are relatively heavy. A further object is to provide such a work handling device as may be quickly and conveniently moved to and from working position and which may be conveniently caused to engage and disengage the work.

Another object of the invention is the provision in a work handling device of means whereby an article may be engaged with its principal axis lying in a given plane, for instance a horizontal plane, and thereafter lifted, conveyed if desirable, and deposited in the same or different location with its principal axis in a plane different from its first given plane, for instance in a vertical plane.

Other objects, which may be obtained with advantage either singly or in combination, are to provide in a work handling device means for pivotally supporting the work engaging elements at or above the center of gravity thereof, means for limiting the angle of relative rotation between the work engaging portion of the device and the lifting handle or bail therefor, means carried by the device for actuating the gripping jaws, and means for conveniently adjusting the working position of the jaws relative to each other to accommodate work pieces of varying size and shape. Further objects and advantages will appear as the description proceeds.

The invention is particularly designed, in the preferred embodiment here shown and described, for association with metal coiling apparatus and for use in intermediate coiled strip handling operations. In this form it may be referred to as a coil handling tongs and may be used to pick up a coil of metal strip resting on a coiler, conveyor, or the like, to convey the coil to a desired destination, and to deposit the coil on a truck, conveyor, or other apparatus. For lifting a coil from a coiler to a truck, it is often desirable to turn the coil through an angle of 90°, from a position on the coiler in which its principal axis is horizontal to a position on the truck in which its principal axis is vertical. The desirability of so handling and arranging the coil will occur for many reasons in strip processing operations, one reason often being that it is desirable to transport coils on end since they are more easily stacked and have less tendency to be injured

when so arranged. To accomplish the purpose of turning a coil through 90° it has heretofore been necessary to employ special equipment or to maneuver the coil manually while it is held by a crane.

The present invention is here described in its preferred embodiment as a coil handling tongs adapted to automatically perform the 90° turnover function, and comprises briefly a work handling tongs pivotally supported from a bail adapted to be carried by a crane or other type of lift, the tongs including oppositely disposed jaws normally resting with their work engaging axis in a given plane and adapted when lifting a coil to automatically rotate with the coil into the desired plane. The clamping jaws are mounted on a main frame to which the bail is pivoted and are adapted to be opened or closed on one radial layer of coil thicknesses, and the main frame carries means for opening and closing the jaws, means for adjusting the relative open position of the jaws independently of the opening and closing means, and suitable stops for limiting the angle of rotation between the frame and the bail. It has been found that by pivotally connecting the bail to the main frame at or above its center of gravity, especially in connection with suitable stops on the main frame for limiting the positions of the bail with respect thereto, the tongs may be conveniently moved about with their unloaded jaws open and in balance. In this condition they are conveniently arranged for engagement with a coil and yet they may be clamped to a coil and lifted, the coil unbalancing the apparatus and automatically assuming a position approximating 90° from its former position.

With reference now to the drawing, the preferred embodiment of the invention may be more particularly described.

In the drawing;

Fig. 1 is a side elevation of a coil handling tongs;

Fig. 2 is a rear elevation, partly in section, of the apparatus shown in Fig. 1;

Fig. 3 is an enlarged section through the cross arm and rotary gland, corresponding to a portion of the apparatus shown in Fig. 2; and

Fig. 4 is an enlarged section through one hinge member and the packing joint associated therewith, corresponding to a portion of the apparatus shown in Fig. 2.

The apparatus comprises a bail or handle, identified generally by the reference numeral 10, and having a tongued lifting portion through which an eyelet 11 has been formed for engagement by a crane hook or clevis pin, the bail supporting a main frame 12 through its component cross arm or bearing carrier 13, legs 14 and 15, hinge pins 16, and hinge members 18, the hinge

pins 16 being secured to hinge members 18 by hinge pin nuts 20, and the hinge members 18 being secured as by bolts to the main frame 12. The main frame 12 preferably comprises an integrally formed work engaging jaw 21, a frame portion to which the reference numeral 12 is directed, and an integrally formed cylinder 22. A suitably bolted cylinder head 23 covers the outer end of cylinder 22, and a piston identified 10 generally by the reference numeral 25 is movable within the cylinder 22, being secured to a piston rod 26 by a suitable nut 27 and comprising a disc 28, a cup leather 29, and a cup leather clamping ring 30 secured to the disc 28 by suitable 15 able cap screws.

The piston rod 26 is axially located at the piston end by the sliding engagement of the piston 25 within the cylinder 22 and at its opposite end by the sliding engagement of a bearing portion 32 within a bushing 33 secured within the main frame 12 adjacent the fixed jaw 21. The piston 25 and piston rod 26 may be considered as a crosshead slideable in ways composed of the cylinder 22 and bearing portion 32, and other 25 crosshead and way construction could be employed.

The piston rod 26 is externally threaded over a major portion of its length between the piston 25 and the bearing portion 32, and carries thereon an internally threaded movable jaw 35 reciprocable toward and away from the fixed jaw 21 through reciprocation of piston rod 26. The threaded portion of piston rod 26 may also have sliding movement in bushing 33. The movable jaw 35 may be positioned axially along the threaded portion of piston rod 26 by rotation of the piston rod, conveniently effectuated through the turning of a removable hexagonal bar wrench 36 adapted to be inserted into a wrench socket 37 within the hollow bore of the piston rod 26. It will appear then that rotation of the piston rod 26 will adjust the position of movable jaw 35, but the operating motion of jaw 35 is preferably obtained by means of the cylinder 22 and 45 a return spring 38 of the compression type located within the hollow bore of piston rod 26 between a seat 39 therein and a retainer plate 40 secured as by cap screws to the main frame 12.

The jaw members 21 and 35 preferably extend 50 at right angles to the axis of the piston rod 26, outwardly away from the main frame 12, where they may more conveniently be caused to engage a coil or other article. For use in picking up coiled strip material the jaw members 21 and 55 35 are formed with work engaging surfaces suitably concave and convex, respectively, and carry suitable composition shoes 43 and 44, respectively, likewise formed to accommodate the curved inner and outer surfaces of coils of 60 variable radial thickness. Thus, in the form of the invention here described, the jaw members 21 and 35 are adapted to engage a horizontal coil at its upper external surface and at its upper internal surface, between which a radial plane is 65 substantially vertical and passes through the substantially vertical axis of the piston rod 26. Suitable other shapes for the jaw members 21 and 35 and for the inserts or shoes 43 and 44 may be conveniently provided where it is desired.

70 For supplying a pressure medium to the cylinder 22 it has been found desirable to employ a conduit for the pressure medium through a pipe line 45 connecting to a stuffing box 46 (Fig. 3) at the top of the bail 10, and passing 75 from the stuffing box through a rotary gland,

identified generally by the reference numeral 47, into a pipe line 48 connecting to the leg 15 and passing therethrough into a packing joint, identified generally by the reference numeral 50, and from the packing joint 50 through a pipe line 51 to the cylinder head 23.

Reference is now particularly made to Fig. 3 wherein the connection of the pipe line 45 to the stuffing box 46 is shown, as is the construction of the rotary gland 47. The rotary gland comprises the stuffing box 46 rotatably secured to the bearing carrier 13 through the medium of a pair of ball bearings 53, the inner races of which are retained between a flange on the lower extremity of stuffing box 46 and a retainer ring 54 15 threadedly secured to the stuffing box 46. Thus it will appear that the bail 10 and apparatus generally are rotatable about a vertical axis with reference to the stuffing box 46 by means of this rotary gland 47.

The rotatable pressure conduit connection through the rotary gland 47 comprises a hollow packing stem 55 rotatably supported within stuffing box 46 through the medium of packing rings 56 and packing gland sleeve 57 adjustably 25 secured to the stuffing box 46 by suitable cap screws. The aforementioned pipe line 48 connects through a suitable coupling from the hollow packing stem 55 to the leg 15 which is also hollow for the passage of a pressure medium. 30

The leg 15 includes, approximately midway in its length, a three-way spring loaded pressure valve 60, having a suitable exhaust port 62, which valve is adapted to control the flow of a pressure medium to and from cylinder 22 and to be 35 operated by a removable square head wrench 61. The hollow leg 15 connects to a hinge stuffing box 64 carrying the hinge pin 16. The stuffing box 64 provides a rotatable gland for the passage of the pressure medium from the bail 10 to the 40 cylinder 22 and is comprised of a hollow packing stem 65, a packing ring 66, a packing member 67, and a packing gland nut 68 adapted to rotatably retain the packing stem 65 within the stuffing box 64. Suitable radial ports and an internal 45 conduit are provided within the packing stem 65 for connecting to a passage within stuffing box 64 connecting to the leg 15 (Fig. 4). The aforementioned pipe line 51 is connected to the packing stem 65 at one end, and through a suitable 50 coupling is connected to the cylinder head 23, the cylinder head 23 having a suitable port therethrough for the passage of the pressure medium into the chamber behind the piston 25.

From the above description it will appear that 55 the work gripping jaws 21 and 35 are supported by a main frame 12 which is pivotally supported, through the medium of the aforementioned hinge pins 16, to the bail or handle 10 for rotation about a horizontal axis. It is to be also noted 60 that the bail 10 is pivoted for rotation about a vertical axis to a tongued lifting portion of stuffing box 46. Thus the apparatus may be readily moved to various desired work engaging positions. Handles 73 are integrally formed on main 65 frame 12 at cylinder 22 for maneuvering the apparatus. Furthermore, it will be noted that means for actuating the jaw 35 are self-contained within the frame 12 in the form of the cylinder 22 and piston 25 in association with 70 the spring 38, and that means for supplying pressure to the cylinder 22 have been arranged so as not to interfere with either rotational movements of the apparatus. By sacrificing the degree of freedom of rotational movement about 75

the vertical axis and the degree of freedom of motion and balancing of the parts around the horizontal axis, other means could be employed for supplying the pressure medium to cylinder 5 22, such as flexible lines hung from the crane or lift and connecting directly to cylinder 22.

For limiting the upward movement of the jaws 21 and 35 toward the upper portion of the bail, that is for limiting the clockwise motion of the 10 frame 12 as viewed in Fig. 1, suitable ears or lugs 10 are provided on the retainer plate 40 adapted to abut against the legs 14 and 15 of the bail 10. Likewise for limiting the rotational movement of the frame 12 in the opposite direction, a stop 71 15 has been provided on the upper portion of the cylinder 22 and also adapted to abut against the leg 14. These lugs 10 and stop 71 are desirable, along with the location of the hinge pins 16 approximately at or above the center of gravity of 20 the apparatus carried by the main frame 12, so that a balanced condition of the tongs will obtain when in either of its extreme positions, such as in Fig. 1; but arrangements could be employed eliminating lugs 10 and stop 71, or eliminating the approximate center of gravity swinging of main 25 frame 12.

Viewing the tongs as shown in Fig. 1, it is contemplated that a coil having its axis running from left to right through the area near the cylinder 30 22 could be engaged at its upper outer surface by the jaw member 21 and at its upper inner surface by the jaw member 35. With the tongs so engaged lifting of the bail 10 would so unbalance the apparatus as to cause the main frame 12 and the lifted 35 coil to turn as viewed in Fig. 1 in a counterclockwise direction until balanced or until stopped, at an angle approximating 90°, by the stop 71. The tongs and its load could then be transported to a desired position and the coil deposited on end. 40 The invention has been described with respect to an apparatus adapted to lift coils from the horizontal position and deposit them in the vertical position. It will be apparent that a moderate rearrangement of the embodiment of the invention here shown could be employed for performing the reverse operation or for performing like operations on the same or other articles. It is intended that the appended claims be read with the understanding that various modifications and 45 changes in the relationship of the parts of the invention may be made without departing from their nature or scope.

What is claimed is:

- 55 1. A work handling device comprising a bail, a main frame pivotally swung from said bail about a single axis, work gripping jaws supported in said main frame, and power means supported by said main frame for positively actuating at least one of said jaws to grip the work.
- 60 2. A work handling device comprising a bail, a main frame pivotally swung from said bail about a single axis, work gripping jaws supported in said main frame, power means supported by said main frame for positively actuating at least one of said jaws to grip the work, and stop means on said main frame for limiting extreme positions of relative rotary movement between said bail and said main frame.
- 65 3. A work handling device comprising a bail, a main frame pivotally swung above its center of gravity from said bail, work gripping jaws supported in said main frame, pressure means supported by said main frame for actuating at least 70 one of said jaws to grip the work, and external

means for directing pressure to said pressure means through said bail and said main frame.

4. A work handling device comprising a bail, a main frame pivotally swung from said bail about a single axis, work gripping jaws supported in said 5 main frame, means for adjusting the maximum opening between said jaws, and separate power means supported by said main frame for positively actuating at least one of said jaws to grip the work.

5. A work handling device comprising a bail, a main frame pivotally swung above its center of gravity from said bail, work gripping jaws supported in said main frame and located substantially above and to one side of its center of gravity, said jaws being adapted to grip work and positively hold the same dependingly therefrom, and a pressure cylinder mounted on said main frame for actuating at least one of said jaws to grip the work, whereby said main frame will be 20 rotatably unbalanced when lifting the work depending from said jaws and will automatically rotate with respect to said bail to assume a new position of balance at an angle approaching a 25 right angle with respect to its unloaded position.

6. A work handling device comprising a fixed jaw, an oppositely disposed movable jaw, means carried by said device for actuating said movable jaw, and a handle for lifting said device pivotally connected thereto near the center of gravity 30 thereof, whereby said device will be in rotational balance when not carrying work.

7. A work handling device comprising a fixed jaw, an oppositely disposed movable jaw, reciprocable power means carried by said device adapted to positively actuate said movable jaw relative to said fixed jaw for gripping the work, separate means for varying the maximum opening between said jaws, and a handle for lifting said device pivotally connected thereto about a 40 single axis.

8. A work handling device comprising a main frame, bearing portions within said main frame, a fixed jaw carried by said main frame, a reciprocable support slidable in said bearing portions, a movable jaw carried by said reciprocable support, and means on said main frame for actuating said support for gripping the work.

9. A work handling device comprising a frame, a fixed jaw attached to said frame, ways disposed longitudinally within said frame, a crosshead disposed within said frame in slidable engagement with said ways, a screw on said crosshead, a movable jaw threadedly engaging said screw and adapted to be moved toward and away from said fixed jaw by rotation of said screw, and means on said main frame adapted to reciprocate said crosshead, whereby the device is capable of grasping articles of different sizes without change in the amplitude of reciprocation of the crosshead.

10. A device for use in association with a lift and adapted to handle coils of material comprising a frame, a pair of oppositely disposed jaws, a reciprocable piston longitudinally disposed within said frame and adapted to open and close said jaws, adjusting means associated with at least one of said jaws adapted to vary the maximum jaw opening, and a lifting bail pivotally connected to said frame substantially at the center of gravity thereof, whereby upon lifting a coil with its axis lying in a given position the coil and frame will automatically rotate with respect to the bail for depositing the coil with its axis at a substantial angle to its former given position.
